PRECOOLING MEANS FOR REFRIGERATOR CARS

Horace Giddings, San Francisco, Calif.

Application July 26, 1932. Serial No. 624,734

5 Claims. (Cl. 62—24)

The present invention relates to refrigerator cars, and more particularly to means for initially and quickly cooling the cargo compartment and its lading.

5 The principal object of the invention is to provide means carried by the car itself but operated by outside electric power, for circulating the interior air of the car successively through its ice and lading compartments, so that the latter, with its contents, will be rapidly cooled. This has the effect of cooling the lading as soon as it is placed in the car, or as soon as the car is iced, whichever step is done first, and may be used instead of the more costly process of 15 pre-cooling the lading in a separate refrigerating plant before it is loaded into the car. Other objects of the invention are to provide suitable means for directing the air in order to insure maximum circulation; to provide suitable housings to protect the motors and circulating fans 20 from water or brine dripping from the ice tanks; and to provide convenient electrical connecting means for supplying current to the motors.

I am aware that attempts have been made to 25 circulate the air in a refrigerator car by mechanism operated by the movement of the car. Such apparatus is available only while the car is in motion. My apparatus, however, can be used while the car is standing and being loaded or 30 iced, so that the lading is cooled immediately. Furthermore, it can be operated at any re-icing station along the car's route, to immediately re-cool the lading if its temperature has risen because of lack of ice.

35 I have herein shown my invention as embodied in a railway refrigerator car of standard construction, using ice as the refrigerant. It will be apparent, however, that the invention may be applied, without material change, to other types of refrigerator vehicles. It should 40 also be understood that the form, construction and arrangement of the several parts herein shown and described may be varied, within the limits of the claims hereto appended, without departing from the spirit of the invention as defined in said claims.

Reference should be had to the accompanying drawings, wherein

Fig. 1 is a longitudinal vertical section of a 50 conventional refrigerator car embodying a preferred form of the invention.

Fig. 2 is a partly broken transverse section, 55 enlarged, showing portions of one ice tank and the bulkhead separating it from the cargo compartment.

Fig. 3 is a longitudinal vertical section of one ice tank, on the same scale as Fig. 2.

Fig. 4 is a sectional plan of one ice tank on the same scale as Fig. 2.

In the drawings, the reference numerals 11, 12, 60 13 and 14 designate respectively the floor, roof, sides and ends of a standard refrigerator car. At its ends are the usual refrigerant compartments or ice tanks 15. The remainder of the car constitutes the cargo compartment 16. The ice tanks 65 15 extend across the entire width of the car, and are separated from the cargo compartment 16 by bulkheads, which are covered with solid planking 17 except for a narrow space 18 at the bottom and a wider space near the top, which is provided 70 with a screen 19.

The frame of each bulkhead consists of vertical posts 20, suitably supported by the shell of the car. The planking 17 and screen 19 are secured to the outside of said posts, and a perforated metal 75 plate 21 is secured to the inside thereof, said plate forming the front wall of the ice tank. The side and rear walls of said tank are formed by screens 22 and 23, secured to posts 24 which in turn are secured to the sides and end of the car. This 80 construction provides vertical air spaces or channels 24 on all sides of the ice tank.

The usual grate 25 is provided in the lower portion of the ice tank, suitably supported in spaced relation above the floor, and adapted to support 85 the blocks of ice with which the tank is filled. A hatch 26 in the roof is provided for introducing the ice. The usual ceiling 27 for the cargo compartment is spaced below the roof.

A false or cargo floor consisting of spaced 90 transverse slats 28 is supported by longitudinal stringers 29 resting upon the main floor 11 between the bulkheads. The height of said false floor above the main floor is approximately the same as the air space 18 at the bottom of the 95 bulkhead, so that air can pass freely from within in the ice compartment under said false floor.

Beneath each ice grate is a housing 30, having vertical side and rear walls 31, and a water tight cover 32 which preferably slopes downward toward both sides, as shown in Fig. 2, and which overhangs the front of the housing, as shown in Fig. 3. In the front wall 33 of said housing is positioned a fan 34, driven by an electric motor 35, said motor being within the housing and protected thereby from the drip from the ice tank above it. The rear wall and the rear portion of the side walls of the housing are provided with louvers 36, which admit air to its interior but exclude dripping water therefrom.

- A forwardly and downwardly extending funnel 37 is secured to the front of the housing 30, and terminates in a low wide mouth 38 which directs the air from the fan 34 under the false floor 28. 5 Diagonal braces 39 extend from the lower front portion of the housing upwardly and outwardly to the bulkhead, and longitudinal braces 40 extend between the lower portion of the bulkhead and the end wall of the car. A drip pan 41, provided 10 with the usual drains 42, covers the floor beneath the ice tank, and suitable supporting spacers 43 are positioned between said pan and the bottom 44 of the motor housing 30.
- The power wires for each motor 35 are led out 15 to one side of the car and thence upwardly in suitable conduits 45. A conduit 46 running the entire length of one side of the car connects the two conduits 45, and the wires from both motors are led through said conduits to a connection box 20 47 positioned on the outside of the car near one end and near the roof, where it is easily accessible from the usual platform, not shown, of an icing plant. The connection box 47 is adapted to receive a suitable detachable plug 48, Fig. 2, by 25 which the fan motors are connected to a source of power such as the lighting or power circuit of the icing plant. The above described arrangement of electrical connections is preferred because it enables the man who ices the car to operate 30 both fans, merely by plugging in the detachable connector 48, at any time during the icing operation.
- It will be readily understood that when the fans 34 are running, warm air from the top of the 35 cargo compartment is drawn into the ice tanks through the space above the solid portion 17 of the bulkhead, thence downwardly through said ice tank and the vertical spaces in its walls, during which time it is cooled by the ice within said 40 tank, thence into the housing 30 through its louvers 36. From said housing the cool air is forced out through the funnel 37 into the space beneath the cargo floor 28, whence it rises through and around the cargo, thus completing its circuit. 45
- By the use of the false floor 28 and the funnel 37, adequate circulation of air is assured. The housing 30, with its tight cover 32 and its air inlet louvers 36, not only protects the motor from water, but insures drawing the air from the coldest 50 region of the ice tank, which is its lower rear portion. The use of electric motors, driven by outside power, enables the cargo compartment to be quickly cooled while it is being loaded, or while the car is being iced, or at any other time when it is standing within reach of an electric power circuit, thus providing an efficient and simple means for pre-cooling the cargo, and eliminating the necessity of separate and costly plants for this purpose. 55
- I claim:—
1. In a refrigerator car having a refrigerant compartment and a cargo compartment, a bulkhead separating said compartments, said bulkhead being spaced from the floor and roof of the car; an apertured false floor in the cargo compartment spaced above the main floor; a fan in the lower portion of the refrigerant compartment, said fan having an air inlet positioned to receive air from said refrigerant compartment; a directing funnel forming the air outlet for said fan, said funnel having a low wide mouth positioned adjacent the floor of the car to direct the air under said bulkhead and said false floor; and means for driving said fan. 8
  2. In a refrigerator car having a refrigerant compartment and a cargo compartment, a bulkhead separating said compartments, said bulkhead being spaced from the floor and roof of the car; a housing positioned in the lower portion of the refrigerant compartment and provided with an air inlet; a directing funnel forming an air outlet for said housing, said funnel having a low wide mouth adjacent the floor of the car to direct the air beneath said bulkhead into the cargo compartment; a fan within said housing; and a motor for driving said fan, said motor being inclosed within said housing. 9
  3. In a refrigerator car having an ice tank and a cargo compartment, a grate in said ice tank; a housing beneath said grate, said housing being spaced from the walls of the car and having air inlet apertures in its rear portion; a water-tight cover for said housing; a fan in said housing; means inclosed within said housing for driving said fan; and a funnel forming an air outlet for said housing, said funnel extending from the front of said housing and having a low wide mouth adjacent the floor of the car for directing the air from said fan into the lower region of the cargo compartment. 100
  4. In a refrigerator car having an ice tank and a cargo compartment, a grate in said ice tank; a housing beneath said grate, said housing being spaced from the walls of the car and having louvers in its rear portion forming air inlet apertures protected against the entrance of water dripping from said grate; a water-tight cover for said housing; a fan mounted in the front wall of said housing; means inclosed within said housing for driving said fan; and a funnel forming an air outlet for said housing, said funnel extending from the front of said housing and directing the air from said fan into the lower region of the cargo compartment. 115
  5. In a refrigerator car having a cargo compartment and an ice tank, said tank having a filling hatch in the upper portion of the car; a grate in said ice tank; a fan beneath said grate; a housing for said fan having an inlet positioned to receive air from said ice tank and an outlet positioned to deliver the air into the lower portion of said cargo compartment; an electric motor for driving said fan; a separable electric connector positioned upon the exterior of the car near said hatch to receive electric power from an outside supply, the position of said connector being such as to permit its manipulation by an operator engaged in icing the car through said hatch; and electric conducting means between said connector and said motor. 125

HORACE GIDDINGS. 140
